UNITED STATES PATENT OFFICE.

WILLIAM N. SPRINGER, OF SOUTH BEND, INDIANA, ASSIGNOR TO AVERY COMPANY,
A CORPORATION OF ILLINOIS.

PLOW.

1,204,828.

Specification of Letters Patent. Patented Nov. 14, 1916.

Application filed December 26, 1912, Serial No. 738,704. Renewed March 30, 1916. Serial No. 87,848.

To all whom it may concern:

Be it known that I, WILLIAM N. SPRINGER, a citizen of the United States, residing at South Bend, in the county of St. Joseph and 5 State of Indiana, have invented certain new and useful Improvements in Plows, of which the following is a specification, reference being had therein to the accompanying drawing.

10 This invention relates to improvements in plows and more especially to improvements in plow bottoms or bodies which are provided with readily detachable plow shares or points. Plow bottoms or bodies embodying my invention can be used as desired either as parts of walking plows, as parts of riding plows, or as parts of engine gang plows.

15 The principal object of the invention is to provide in a plow body having a detachable share, improved mechanism adapted to readily lock the share in place and to permit its easy removal.

20 Of the accompanying drawings which illustrate one embodiment of the invention, —Figure 1 is a perspective view taken looking at the plow from beneath. Fig. 2 is a detail cross sectional view through the locking mechanism. Fig. 3 is a detail view 25 of the locking mechanism detached from the other parts of the plow body.

25 Referring to the drawings, —1 represents the frog upon which the other parts of the plow are mounted. This frog is preferably formed of sheet metal and is forged into the proper shape. The frog may be secured by means of bolts or rivets to the plow stand- 30 ard 2.

35 3 is the moldboard which is riveted or bolted to the frog, and 4 is the landside which is also secured to the frog. The moldboard and landside are connected by a reinforcing brace 5. It will be understood that under some circumstances the landside may 40 be omitted and I do not therefore limit my invention to a plow body having a landside.

45 6 represents as a whole the detachable point or share. This share is shaped at its rear side to engage and aline with the land- 50 side and the moldboard at its lower end in-

ner side to engage with and be supported by the parts of the frog to which the moldboard and landside are respectively connected. Projecting downward from the lower side of the moldboard section of the share 55 is a pin or button 7. This is provided at its outer end with a flange or collar for a purpose to be described.

8 is a bracket mounted upon the main part of the plow body. This bracket is preferably a strip of metal which is bent to provide two end parts adapted to engage respectively with the frog and the moldboard, and a central part in a plane at an angle to the plane of the end parts. The end parts 60 of the bracket 8 are preferably secured to the under sides of the frog and the moldboard, but it will be understood that there may be variation as to the exact form and mode of attachment of the bracket. Preferably as shown in the drawings, one end of the bracket 8 is carried forward so as to provide a support for the outer part of the moldboard.

65 The central part of the bracket 8 is provided at 9 with a non-circular and preferably rectangular aperture. Through this aperture 9 there extends a link 10 which is pivoted at its rear end to a cam lever 11. The lever 11 is forked at its inner end to embrace 70 the link 10 and the two forks of the lever are provided at 12 with cam surfaces adapted to engage the surface of the bracket 8. The cam is provided with a flat portion 75 adapted to engage the bracket when the share is drawn into its operative position. This flat surface serves to prevent accidental movement of the cam lever to release the share. The link 10 has two parts, the rear part 13 which extends through the aperture 90 9 having a socket 14 into which is screwed the end of the front part which is a bolt 15. The rear part of the link is non-circular and preferably rectangular in cross section and its engagement with the walls of the aperture 95 9 prevents turning. The bolt has an eye at 16 adapted to engage the button 7 on the share. The eye 16 is large enough to permit the flange at the end of the button to pass through, and the flange serves to pre- 100

vent the accidental removal of the bolt after it is once in place.

In operation when it is desired to secure the share in place it is simply necessary to engage the eye of the bolt 15 with the button 7 on the share and then to swing the lever 11 into the position shown in the drawing. This causes the cam surfaces at 12 to press against the surface of the bracket 10 and force the link 10 backward. Tension is transmitted through the link 10 to the share, the result being that the share is forced backward into firm engagement with the other parts of the plow body. When it is desired, for any reason, to remove the share, this can be done simply by swinging the lever 11 into a position at an angle to the link 10, sufficient play thus resulting to permit the button 7 to be removed from the eye 16. It will be observed that by means of the threaded engagement of the bolt 15 with the rear part 13 of the link 10, a certain amount of adjustment is possible. By properly adjusting these two parts the plowman is enabled to secure the proper tension on the share when the lever 11 is swung backward to its operative position.

I am aware that plow bodies having detachable shares have been heretofore proposed and used and I do not therefore broadly claim such a construction to be my invention. Most earlier devices with which I am familiar have involved the use either of bolts or nuts, or more or less complicated lever mechanisms. Bolts and nuts are objectionable for the reason that wrenches are required to operate them, and are further objectionable for the reason that the nuts may become tight on the bolts from any of a variety of causes, such as mechanical injury to the threads, rust, or accumulation of dirt. The other earlier proposed devices with which I am familiar have involved mechanisms comprising systems of levers objectionable because of their complexity and liability to injury. The mechanism embodying my invention is free from the objections incident to earlier devices, for the reason that it has no nuts which must be turned and has but a single pivotal connection which is so located that it can be easily cared for and lubricated when necessary. The parts of my mechanism are relatively simple in outline and there are no projections and angles, which might accumulate an undue amount of dirt and trash. The normal position of the locking lever 11 is parallel to the line of draft and there is therefore no tendency for it to be moved to an inoperative position by engagement with stationary objects.

What I claim is:—

1. In a plow body, the combination with a frog and a moldboard secured thereto, of

a detachable share adapted to engage the frog and the moldboard, a longitudinal link comprising two parts relatively movably connected to permit adjustment in total length, means for connecting the forward end of the link to the share, and means for tensioning the link to draw the share into place and secure it, the said means comprising two engaging elements one of which is movable relatively to the other, one of the said elements being carried by the link and having a fixed point of connection thereto.

2. In a plow body, the combination with a frog and a moldboard secured thereto, of a detachable share adapted to engage the frog and the moldboard, a longitudinal link comprising two parts threaded together to permit adjustment in total length, means for manually detachably connecting the forward end of the link to the share, and means for tensioning the link to draw the share into place and secure it, the said means comprising two engaging elements one of which is movable relatively to the other, one of the said elements being carried by the link and having a fixed point of connection thereto.

3. In a plow body, the combination with a frog and a moldboard secured thereto, of a detachable share adapted to engage the frog and the moldboard, a bracket connected to the frog and moldboard and having an aperture, a link extending through the aperture and comprising two parts threaded together to permit adjustment in total length, means for manually detachably connecting the forward end of the link to the share, and a lever pivoted to the rear end of the link and provided with a cam surface adapted, when the lever is moved, to engage the bracket and tension the link, whereby the share is drawn into place and secured.

4. In a plow body, the combination with a frog and a moldboard secured thereto, of a detachable share adapted to engage the frog and the moldboard, a bracket connected to the frog and moldboard and having a non-circular aperture, a link extending through the aperture and approximately fitting it, the said link comprising two parts threaded together to permit adjustment in total length, means for detachably connecting the forward end of the link to the share, and means for tensioning the link to draw the share into place and secure it.

5. In a plow body, the combination with a frog and a moldboard secured thereto, of a detachable share adapted to engage the frog and the moldboard, a bracket connected to the frog and moldboard and having an aperture, a link extending through the aperture, means for connecting the forward end of the link to the share, and a lever pivoted to the rear end of the link and

provided with a cam surface adapted, when the lever is moved, to engage the bracket and tension the link, whereby the share is drawn into place and secured, the said cam 5 having a flat part engaging a corresponding flat part of the bracket when the share is in place.

In testimony whereof I affix my signature, in presence of two witnesses.

WILLIAM N. SPRINGER.
